UNITED STATES PATENT OFFICE.

HENRY BERSCHNEIDER, OF SUMMER HILL, PENNSYLVANIA.

NUT-LOCK.

SPECIFICATION forming part of Letters Patent No. 629,647, dated July 25, 1899.

Application filed May 20, 1899. Serial No. 717,656. (No model.)

To all whom it may concern:

Be it known that I, HENRY BERSCHNEIDER, a citizen of the United States, residing at Summer Hill, in the county of Cambria and State of Pennsylvania, have invented new and useful Improvements in Nut-Locks, of which the following is a specification.

This invention relates to improvements in nut-locks, the object being to provide a nut-lock which is simple in construction and which can be readily applied and manipulated so as to release the nut without injury to the parts; and the invention consists in the combination, with a bolt of ordinary construction, of a nut having ratchet-teeth which extend across the sides, a washer and locking-bar made of a single piece and having a spring member which projects from the washer so as to engage with the ratchet-teeth of the nut, and means for holding the washer against rotation, as will be hereinafter set forth.

In the accompanying drawings, Figure 1 is a perspective view of a nut-lock constructed in accordance with my invention, the same being applied to the fish-plate of a railroad-rail. Fig. 2 is a plan view, the rail and fish-plates being shown in section. Fig. 3 is a perspective view of the combined washer and locking-bar; and Fig. 4 is a front elevation, the locking-bar being shown in section.

In the annexed drawings, A refers to a bolt which is of ordinary construction, one end of the same being held against rotation in the usual manner. The nut B is preferably hexagonal, is of the standard thickness, and the angles or corners extend across the entire sides of the nut, the faces being cut away, so as to provide indentations or ratchet-teeth b b. In forming the ratchet-teeth or grooves b b, they are cut or formed in the nut so that there will be a flat portion of comparatively narrow width adjacent to the straight edge of the ratchet-teeth, as shown at b', and on the other side, adjacent to the inclined portion b² of the ratchet-teeth, are wide flat faces b³, which are on a line with the narrow flat faces b', such faces being arranged on opposite sides of the nut, so as to provide flat surfaces with which the jaws of an ordinary wrench may engage without contacting with the straight shoulders of the ratchet-teeth. This construction also provides a nut which

can be readily turned by a wrench having fixed jaws which may incline or converge toward each other. A nut thus constructed 55 will have one wide face b³ opposite one of the narrow faces b', and the depression or ratchet-tooth will be positioned between these flat bearing-surfaces. This type of nut can be readily manufactured and is internally 60 threaded in the usual manner.

The combined washer and locking-bar is made up from a strip of spring metal or steel, the same being bent to form a circular portion or washer c, one end being slightly reduced and bent at right angles to form a lug c', while the other end is bent in an opposite direction and slightly inward, so that it will have a spring tendency at an acute angle to the plane of the face of the washer. One of 70 the sides of the spring-arms c² is beveled or rounded, as shown in Fig. 4, so that said rounded or inclined portion may readily ride over the ratchet-teeth of the nut, and the end of the spring-arm is preferably formed into 75 an eye c³, so that it can be readily grasped to hold the same out of contact with the nut, especially when it is desired to remove the nut from the bolt.

In instances where the nut-lock is used in 80 connection with fish-plates of railway-rails the fish-plates will have indentations or recesses which receive the lug c', and when such recesses are not provided and the washer is used to bear against a wooden surface the end of 85 the lug may be pointed to readily enter the wood.

The internal diameter of the washer is considerably larger than the external diameter of the bolt, and as the nut is turned and contacts with the face of the washer the lug will act as a pivot, so as to swing the washer on the lug and bring the spring-arm nearer to the bolt and face of the nut, it being obvious that as the nut is turned the arm will give to 90 act as a pawl and prevent the nut turning in an opposite direction. To release the nut, the spring-arm may be drawn out of the ratchet-tooth with which it engages, and when the nut has been given a turn sufficient to 100 loosen it the washer can be swung upon the lug to bring the arm out of the path of the ratchet-teeth. The device hereinbefore described is simple in construction, can be man-

ufactured at a low cost, and is efficient and practical.

Having thus described my invention, what I claim as new, and desire to secure by Letters 5 Patent, is—

1. In a nut-lock the combination with a bolt and a nut having ratchet-faces, of a combined washer and spring locking-arm the washer having a lug which projects in an opposite direction from the projection of the spring-arm, the diameter of the opening in the washer being considerably greater than the diameter of the bolt and less than the diameter of the nut, for the purpose set forth.

2. In a nut-lock the combination with a bolt 15 and a nut having ratchet-teeth which extend across its sides, of a combined washer and locking-bar, the locking-bar having a face inclined on one side, the washer being provided with means for holding it against rotation. 20

In testimony whereof I have hereunto set my hand in presence of two subscribing witnesses.

HENRY BERSCHNEIDER.
